(57) **CLAIM**

The ornamental design for a throttle body for internal combustion engine, as shown and described.

DESCRIPTION

FIG. 1 is a front view of an embodiment of a throttle body for internal combustion engine of my new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a first perspective view thereof;

FIG. 8 is a second perspective view thereof;

FIG. 9 is a third perspective view thereof;

FIG. 10 is a fourth perspective view thereof; and,

FIG. 11 is a fifth perspective view thereof.

The broken lines depict portions of the throttle body for internal combustion engine that form no part of the claimed design.

The dot-dash lines define the bounds of the claimed design and form no part thereof.
